GAS BURNER

Trygve Forberg, New York, N. Y., assignor, by
mesne assignments, to Servel, Inc., Dover,
Del., a corporation of Delaware

Application May 19, 1934, Serial No. 726,493

4 Claims. (Cl. 158—106)

My invention relates to gas burners and more particularly to burners of the type in which gas is mixed with air prior to emission of the gas from the burner, such as, for instance, Bunsen type burners in absorption refrigeration apparatus.

It is an object of my invention to provide a gas burner of such type in which stoppage of primary air caused by deposit of foreign particles such as dust and lint is substantially eliminated, whereby the gas burner will require a minimum amount of attention.

In accordance with my invention, primary air flows to the burner from a point immediately adjacent the burner flame and in a direction substantially opposite to the direction of air flow at the flame, whereby the air is cleansed of lint, dust, and other foreign particles by the combined effects of inertia and incineration.

The nature of my invention and the objects and advantages thereof will be more fully apparent upon consideration of the following description and the accompanying drawings forming a part of this specification and of which:

Fig. 1 is a sectional view of a gas burner embodying my invention;

Fig. 2, an end view of the burner;

Fig. 3, a top view of the burner; and

Fig. 4, a side view of the burner mounted in position for heating the generator of an absorption type refrigerator.

Referring more particularly to Fig. 1 of the drawings, the burner body 10 is provided with a gas supply passage 11, suitably threaded at its upper end, 12, for connection to a gas supply pipe. In the upper portion of passage 11, there is inserted what may be generally referred to as a safety cut-off valve assembly 13, comprising a valve body 14, a valve member 15, a valve stem 16, a snap action thermostatic diaphragm 17, a diaphragm housing 18, and a heat conductor 19. The valve member 15 is connected by the valve stem 16 to the center of the thermostatic diaphragm 17, the periphery of which is secured in the housing 18. The heat conductor 19 has one end located in a position to be heated by the burner flame and the other end secured to the housing 18, so that when the burner is lighted heat is conducted to the thermostatic diaphragm 17.

A second passage 20, in the lower part of the burner housing communicates at one end with the lower part of the passage 11 through an opening 21. The effective area of this opening is adjustable by turning an adjustment screw 22,

which is threaded into the lower end of the passage 11. The internal threads are shown only in outline in the interest of clarity. A suitable cap screw 23 is provided for sealing the lower end of the passage 11 and is removable for permitting access to the adjustment screw 22. The adjustment screw 22 may be referred to as the maximum flame adjustment screw, as its setting determines the maximum flow of gas to the burner, and therefore the maximum size of the 10 burner flame. The other end of the passage 20 is permanently sealed by a plug 24. A third passage 25 extends through the burner housing and intersects the passage 20 substantially at right angles. On the exterior of a boss at the 15 upper end of the passage 25 is threaded the lower end of a cylindrical housing 26, providing a mixing chamber 27 at the upper end of the passage 25. In the upper end of passage 25 is threaded a member 28 having a chamber 29, referred to as 20 the orifice well, communicating at its lower end with the passage 25, and a small orifice 30 opening from the upper end of the orifice well 29 into the mixing chamber 27.

The housing 26 is provided with air ports 31 25 for admission of primary air to the mixing chamber 27. On the housing 26 is journaled a sleeve 32 provided with openings corresponding to the air ports 31. This sleeve is referred to as the air shutter and it will be understood that the turning 30 of this shutter adjusts the size of the air ports 31 and therefore the admission of primary air to the mixing chamber 27. In the lower part of the passage 25 is threaded a member 33, which may be referred to as a turbulator. This member is 35 formed with a head 34, which is preferably designed to give a swirling motion to the gas entering the orifice well 29. The lower end of the passage 25 is sealed by a suitable cap screw 35, which is removable to allow adjustment of the 40 turbulator 33. The housing 26 is formed with a restricted portion or partition 36 which is provided with a passage 37 opening into the top of the mixing chamber 27 and in line with the orifice 30. In the upper end of the passage 37 45 is threaded the lower end of the burner tube 38. The upper end of the burner tube is provided with a cap 39 having suitable openings 40. A tube 41 is positioned concentrically around the burner tube 38. The lower end of the tube 41 is 50 secured by screws 42 to the upturned rim 43 of a flange on the lower end of the air shutter 32. The upper end of the tube 41 terminates closely adjacent the openings 40 in the burner cap 39. Suitable lugs 44 may be provided on the burner 55

cap 40 to aid in maintaining the upper end of the tube 41 in position concentrically with respect to the burner tube.

The air shutter 32 may be adjusted by turning the tube 41, the projecting heads of the screws 42 providing suitable finger grips for this purpose. Displacement of the air shutter 32 is prevented by an overturned portion 45 at the upper end of the housing 26 and suitable tension for retaining the air shutter 32 in its adjusted position is provided by resilient arms 46 cooperating with a groove 47 in the housing 26. The arms 46 may be formed by striking out portions of the air shutter 32 which is fabricated of resilient metal.

In operation, a flame is applied to the heat conductor 19, which raises the temperature of the thermostatic diaphragm 17 until the latter snaps to a position opposite that shown in Fig. 1, opening the safety cut-off valve 15. Gas enters the inlet 12 and flows through passage 11, opening 21, passage 20, passage 25, orifice well 29, and the orifice 30 into the mixing chamber 27. As gas passes through the burner orifice, primary air is entrained through the air ports 31. The resulting mixture of air and gas flows through passage 31, burner tube 38, and the openings 40 in the burner cap 39 where the secondary air is encountered and combustion takes place.

The flame impinges upon the conductor 19 so that the temperature of the thermostatic diaphragm 17 is maintained sufficiently high for the valve 15 to remain open. If, for any reason, the burner flame becomes extinguished, the conductor 19 and thermostatic diaphragm 17 cool down until the diaphragm flexes back to the position illustrated in Fig. 1, snapping the valve 15 to its closed position, thus cutting off flow of gas to the burner.

During operation of the burner, the primary air which enters the mixing chamber 27, as previously described, has been drawn downwardly through the tube 41 from the region of the secondary air immediately adjacent the burner flame above the cap openings 40. Around the upper end of the tube 41 and the burner cap 39, the flow of air is in the direction of the burner flame. This is due to heating of the air and movement of the gas and air mixture issuing through the cap openings 40 and the movement of the products of combustion. This movement of air is indicated generally by the arrows outside of the tube 41, in Figs. 1 and 4. Air which is drawn downwardly in the tube 41, as previously described, therefore undergoes a substantial reversal in direction adjacent the upper end of the tube. Due to their inertia, particles of dust, lint, and the like tend to continue in the direction established by the burner flame, thereby deserting the air which is drawn downwardly in the tube 41. The close proximity of the upper end of the tube 41 to the burner flame causes incineration of dust particles or lint including those which may not have been separated from the air during its flow reversal, thereby insuring delivery of clean primary air to the mixing chamber 27. The tube 41 may therefore be referred to as a dust prevention tube. Tube 41 should extend upwardly as far as possible without blocking off the supply of secondary air to the burner.

The location of the open end of the dust tube 41 with respect to the burner flame is of critical importance in carrying out the present invention. If the end of the dust tube 41 is too far below the burner flame, dust will remain in the primary air entering the dust tube. If the open

end of the dust tube 41 is in the combustion area of the burner flame, products of combustion will be drawn into the primary air inlet, and the dust tube will become heated by the flame. It is therefore necessary to locate the open end of the dust tube 41 as close to the burner flame as possible without causing suction of products of combustion. As indicated by the arrows in Figs. 1 and 4, air flow within a certain distance of the burner flame is in a direction opposite to flow of air sucked into the dust tube 41, therefore, if the open end of the dust tube is extended within this distance of the flame, air drawn into the dust tube 41 must undergo an abrupt reversal in direction of flow. On account of inertia, particles of dust, lint, and other foreign matter continue on far enough to be removed from the effect of the suction into the dust tube and are incinerated by the flame or carried on into the flue 49 into which the flame is projected as described below. It will now be understood that if the dust tube 41 does not project within said proper distance of the burner flame, air will be sucked into the dust tube from a zone in which there is no definite trend of air flow or in which the air flow is only at an angle to the dust tube, in which case the suction would overcome the inertia of dust particles and other foreign matter which would be drawn in with the primary air supply. Due to the high temperature immediately adjacent the burner flame, there is some dust removal effected by incineration, but in carrying out the invention, the important factor is the direct opposition of the primary air suction and flow of air in a zone adjacent the burner flame, whereby the inertia of foreign particles carries them into the secondary rather than the primary air stream.

In Fig. 4, the previously described burner is shown mounted in relationship to the heating flue of a generator in an absorption type refrigerator. Since the refrigeration apparatus forms no part of the present invention, there is shown only one end of the generator 48, provided with a heating flue 49. The burner is slidably and rotatably mounted on a rod 50. The burner is adjusted so that the flame is suitably projected into the end of the heating flue 49, and then secured by tightening the screw 51. It will be understood that this relative position of the burner and generator is substantially the same whether the generator be of the horizontal or vertical type. With the burner thus arranged so that the flame projects into the end of a flue, the reversal in the direction of air flow, previously described, is accentuated for the reason that a distinct current of secondary air is carried into the flue by the action of the burner flame, and the primary air is withdrawn through the burner dust tube 41, in a substantially opposite direction.

What I claim is:

1. In a gas burner, a cylindrical housing forming a mixing chamber having a gas inlet orifice and air inlet ports, a burner tube extending from one end of said mixing chamber in line with said gas inlet orifice, an air shutter comprising a perforated sleeve journaled on said housing and having a flange at one end, a dust prevention tube located concentrically around said burner tube and shutter in spaced relation thereto, one end of said dust tube being secured to said flange and the other end of said dust tube terminating immediately adjacent the end of said burner tube, said dust tube, air shutter, and burner tube,

5. tube cooperating to form a substantially annular passage for primary air from a point immediately adjacent the burner flame to said air inlet ports, and a perforated cap on the end of said burner tube having radial projections extending into sliding engagement with the inner surface of said dust tube to space the open end of the dust tube with respect to said burner tube.
2. In a gas burner, a mixing chamber having 10 a gas inlet orifice and air inlet ports, a burner tube extending from the mixing chamber in line with the gas inlet orifice, and means forming a passage for air to said air inlet ports and including a conduit having an open end so located 15 adjacent the end of said burner tube that the open end of said conduit is in a zone next the burner flame in which flow of air induced by the flame is in a direction opposite to the direction of flow of air into said conduit, whereby 20 particles of dust and the like in air flowing in said opposite direction continue to move in that direction due to their inertia and are thus removed from air drawn into said conduit.
3. In a gas burner, a mixing chamber having 25 a gas inlet orifice and air inlet ports, a burner tube extending from the mixing chamber in line with the gas inlet orifice, and means forming a passage for air to said air inlet ports and including a tube located concentrically around said 30 burner tube in spaced relation thereto and having an open end so located adjacent the end of

said burner tube that the open end of said air conducting tube is in a zone next the burner flame in which flow of air induced by the flame is in a direction opposite to the direction of flow of air into said air conducting tube, whereby particles of dust and the like in air flowing in said opposite direction continue to move in that direction due to their inertia and are thus removed from air drawn into said air conducting tube.

4. In a gas burner, a mixing chamber having 10 a gas inlet orifice and air inlet ports, a shutter for adjusting said air inlet ports, a burner tube extending from the mixing chamber in line with the gas inlet orifice, and means forming a passage for air to said air inlet ports and including 15 a dust prevention tube located concentrically around said burner tube in spaced relation thereto, said dust prevention tube being connected to said air shutter for adjustment thereof and having an open end so located adjacent the end 20 of said burner tube that the open end of said dust prevention tube is in a zone next the burner flame in which flow of air induced by the flame is in a direction opposite to the direction of flow of air into said dust prevention tube, whereby 25 particles of dust and the like in air flowing in said opposite direction continue to move in that direction due to their inertia and are thus removed from air drawn into said dust prevention tube.

TRYGVE FORBERG.
